FIG. 1

FIG. 2

FIG. 1 is a perspective view of a golf ball mold showing our new and ornamental design.

FIG. 2 is a top view of the golf ball mold of FIG. 1. The dominant feature of our design resides in the arrangement of protrusions in the interior of the mold, which arrangement is characterized by the close proximity of adjacent protrusions and the lack of protrusions in the central portion of the mold.

We claim:

The ornamental design for a golf ball mold, substantially as shown and described.
